METAL-CUTTING SHEARS

Willie M. Shoffner, Dayton, Ohio

Application April 9, 1949, Serial No. 89,133

9 Claims. (Cl. 30—241)

1

This invention relates to shears for cutting metal sheet and the like and particularly to shears especially adapted for taking relatively heavy cuts and for cutting around corners.

Metal cutting shears according to the prior art generally consists of scissor-like arrangements in which the two legs are cast or forged and are formed with hand grips at one end and with cutting edges at the other end. The legs are pivoted together by a central pin about which the legs rotate relatively in operation.

One serious drawback with a shears constructed in this manner is that only a relatively thin piece of metal can be cut. If it is attempted to cut very heavy material, say greater than a sixteenth, then considerable difficulty is encountered not only in making the cut but in keeping the jaws from sliding over the metal instead of actually cutting through it.

Another drawback in connection with prior art shears which are constructed like scissors is that it is practically impossible to take two consecutive cuts at widely divergent angles unless at least one of the cuts extends considerably beyond the point of intersection of the cuts. It is even with some difficulty that curves are cut with the prior art type shears.

It is evident that the utility of prior art metal cutting shears is definitely limited, especially in connection with artisans installing heating systems and the like and who must be able to form many shapes from sheet metal.

The primary object of the present invention is to provide a metal cutting shears construction which overcomes the aforementioned disadvantages of prior art metal shears.

Another object is to provide a metal cutting shears which can be constructed entirely of ~~stamped and formed~~ parts rather than from casting and forgings if desired.

It is a particular object to provide a metal shears construction such that the shears are capable of cutting metal much heavier than can be cut by shears constructed according to prior art practices.

Another particular object of this invention is to provide a metal cutting shears arrangement especially adapted for cutting around corners and sharp curves.

These and other objects and advantages will become more apparent upon reference to the following description taken in connection with the accompanying drawings in which:

Figure 1 is a side elevation of a shears constructed according to my invention partly broken out in order to show the construction and arrangement of the operative parts thereof;

Figure 2 is a view like Figure 1 but is taken from the other side thereof;

Figure 3 is an end view looking in from the left end of Figure 1;

Figure 4 is a view looking as indicated by the arrow 4 in Figure 1;

Figure 5 is a view like Figure 1 but showing

2

the shears blades moved together at the end of a cutting operation;

Figure 6 is a sectional view indicated by the line 6—6 on Figure 2;

Figure 7 is a plan section indicated by line 7—7 on Figure 2;

Figures 8 and 9 are vertical sections indicated by lines 8—8 and 9—9 on Figure 2;

Figure 10 is a vertical sectional view indicated by line 10—10 on Figure 3;

Figure 11 is a view looking up from beneath a sheet of metal being cut by the shears with the shears turned ninety degrees to the direction of the previous cut for taking a new cut; and

Figure 12 is a view like Figure 11 but looking from the top side of the sheet of metal.

Referring to the drawings somewhat more in detail the shears of this invention generally comprises a frame 10 having a handle means 12 at one end thereof and comprising a pair of spaced side plates 14 rigidly interconnected as by rivet means 16 and having between their ends opposite the handle 12 a spacing member 18. At the handle end there may be the spacer 20 which maintains the side plates 14 in substantial parallelism.

Spaced from the spacer 18 is a part 22 secured between the side plates 14 by rivets 24 and having a dependent portion 26. At the lower end of the dependent portion 26 is a laterally offset foot part 28 extending toward the end of frame 10 opposite the handle 12 thereof.

As will be seen in Figures 2 and 3 the inner side of the foot part 28 is formed so as to have a cutting edge 30. This cutting edge 30 cooperates with a similar cutting edge 32 on the lower end of a bar 34 which is reciprocable in the rectangular passage formed in the frame 10 between the side plates thereof, the spacing member 18, and the blade part 22.

The bar 34 has a notch in its side at 36 which receives the end of the bar 38 that has its other end swivelly supported in the frame 10 as at 40. A spring 42 acts between part 22 and bar 38 and thus continuously urges bar 34 upwardly in its guiding passage.

The spacer member 18 is extended upwardly above frame 10 and receives a pivot pin 44 which mounts the left end of an upper handle or lever 46. Lever 46 carries a roller 48 as by pin 50 and the said roller bears on the upper end of bar 34 as indicated in Figures 1 and 5.

Bar 34 may have a cam shaped upper surface as at 52 if so desired. Roller 48 may have flats 54 on the side toward member 18 to provide clearance for movement of lever 46 and these flats may also act as stops to predetermine the limits of movement of lever 46.

Reference to Figures 2, 3, 6 and 7 will reveal that interposed between one side of bar 34 and one of the side plates 14 of the frame is a plate 56 split part way up as at 58 in alignment with one edge of bar 34. A set screw 60 and clamping

nut 62 provide means for adjusting the part of plate 56 adjacent bar 34 for maintaining the said bar in proper cutting alignment with cutting edge 30 on foot bar 28.

This provides a ready takeup for clearances introduced around bar 34 by manufacturing tolerances and by wear.

Regarding dependent part 26 and foot part 28 of the blade fixed in frame 10, it will be noted that the said part 26 is relieved as at 64 by an undercut extending axially along part 26 and in substantial alignment with the cutting edges 30 and 32. This relief permits turning of the shears to some extent in the material being cut to follow a straight line or a curve.

The foot part 28 is relieved by transversely extending recess 66 which is substantially in alignment with the rear edge of bar 34. This recess is of advantage in permitting the shears to be turned sharply at the end of a cut in order to take a new cut in a different direction.

This is indicated in Figures 11 and 12 where in the first cut taken by the shears is marked 68 and the cut to be taken marked 70. It will be seen that the shear blades have been turned at substantially ninety degrees to their former direction and that the new cut 70 will register exactly with former cut 68.

It will be observed that cutting edges 30 and 32 are somewhat divergent toward the front of the shears as will best be seen in Figures 1 and 2 and that the bar 34 is beveled off at its lower end as at 72 and that its point may be relieved as indicated at 74.

The location of pivot 44 forwardly of bar 34, and the location of the bearing point of roller 48 on bar 34 forwardly of its median line is of importance in keeping the shearing force at a minimum and in preventing the development of high turning movements on the said bar.

It is also to be noted that when the shears are in their open position as shown in Figure 1 the line connecting the central axes of pivots 44 and 50 is substantially parallel with the cutting edges of the blades. Thus, when the lever 46 is moved down to its Figure 5 position the mechanical purchase of the lever on blade 34 actually increases. This is distinctly different from the action of the usual type scissor-like shears where the force available for shearing the metal decreases as the cut proceeds.

It will also be noted that due to the reciprocating motion which blade 34 takes, the divergence between the cutting edges 30 and 32 is considerably less than that found in the usual scissor-type shears. This is effective for eliminating to a great extent the tendency for the shears to slip on the metal when heavy cuts are being taken.

In operation, a sheet of metal to be cut is inserted between the opened blades as indicated by the dot-and-dash outline in Figure 1. The lever 46 is then moved downwardly toward handle 12 until the shears occupy their Figure 5 position. This concludes the cut and if a new cut is to be taken in the same direction the shears are merely again opened and advanced to take a new bite. If a new cut is to be taken in a different direction then the shears are opened, advanced and turned.

It will be noted that because of the dependent position of the cutting edges relative to the frame of the shears the metal being cut offers no hindrance to the shears operator as is customarily the case with the usual type shears.

Also, the lower shears blade is substantially

stationary and acts as an anvil so that little or no deformation of the material being cut takes place. The reciprocatory nature of the blade 34 and the high mechanical advantage of lever 46 permit heavy cuts to be taken. Also, as much or more thrust is available at the end of a cut as is available at the beginning thereof due to the lever and roller arrangement of this invention.

It will also be noted that all of the parts of the shears of this invention can be made from stamped and press formed parts if desired and this offers a substantial saving over casting or forging of the parts.

It will be understood that this invention is susceptible to modification in order to adapt it to different usages and conditions and, accordingly, it is desired to comprehend such modifications within this invention as may fall within the scope of the appended claims.

I claim:

1. In a shears having a frame including a handle at one end; a first blade fixed in said frame adjacent the other end and dependent therefrom, a second blade reciprocable in said frame in a direction generally perpendicular to the length of the frame, said blades having adjacent cutting edges generally perpendicular to the direction of reciprocation of said second blade, a lever pivoted on said frame between said second blade and the said other end of the frame, a roller on said lever bearing on the end of said second blade opposite the cutting edge thereon, and resilient means acting on said second blade for urging it away from said first blade to permit material to be cut to be inserted therebetween, the said roller bearing on said second blade between the median line thereof and the side thereof toward the pivot for said lever.

2. In a hand shears especially adapted for cutting metal, first and second handle means pivoted together at one end, one of said handle means having a member dependent therefrom adjacent said one end and with a foot part extending toward the said one end having a cutting edge along the side toward the said handle, said one handle means having a rectangular passage therethrough with one side wall coplanar with said cutting edge, a bar slidable in said passage having a cutting edge on its one end for cooperation with the cutting edge on said foot part for shearing metal and the like, and a roller on the other handle means positioned to engage the other end of said bar for actuating it in shearing movements, said member being relieved in a line with said cutting edges, and said foot part being relieved by a transverse recess on its underneath side immediately opposite the rear edge of said bar.

3. In a shears: a frame comprising spaced plates having spacing means therebetween and means rigidly interconnecting said plates and spacing means; a first bar rigid in said frame spaced from one of said spacing means to define a rectangular passage in the frame and having a laterally offset foot part extending lengthwise of the frame, said foot part having a cutting edge aligned with one side wall of said passage, a second bar slidable in said passage and having a cutting edge on the end toward said foot part for cooperation with the edge thereon, a lever pivoted in said frame, and a roller on said lever overlying the other end of said second bar whereby substantially all of the thrust on said second bar due to cutting loads is exerted axially thereof, a notch in one edge of said second bar, a member

having one end in said notch and its other end swivelly supported by said frame, and spring means acting on said bar to retract said second bar to separate said edges.

4. In a shears: a frame comprising spaced plates having spacing means therebetween and means rigidly interconnecting said plates and spacing means, a first bar rigid in said frame spaced from one of said spacing means to define a rectangular passage in the frame and having a laterally offset foot part extending lengthwise of the frame, said foot part having a cutting edge aligned with one side wall of said passage, a second bar slideable in said passage and having a cutting edge on the end toward said foot part for cooperation with the edge thereon, a lever pivoted in said frame, and a roller on said lever overlying the other end of said second bar whereby substantially all of the thrust on said second bar due to cutting loads is exerted axially thereof, and a plate member between said second bar and the other side wall of said passage adjustable for keeping said second bar closely confined in said passage.

5. In a shears comprising a frame extending generally longitudinally and having handle means at one end, a bar rigid with said frame between its ends and having an integral foot part offset laterally therefrom and extending toward the other end of the frame, the inner side of said foot part having a cutting edge on its upper side, another bar vertically reciprocable in said frame so as to pass closely by said inner side of said foot part and having a cutting edge on its lower end to cooperate with the cutting edge on said foot part, a lever overlying said handle means and pivoted to the other end of said frame beyond said other bar, and a roller on said lever engaging the upper end of said other bar so relative movement of the lever and frame will actuate said other bar in cutting movements, said roller having a flat thereon adapted to engage the frame and halt the lever in at least one of its extreme positions of movement.

6. In a shears comprising a frame extending generally longitudinally and having handle means at one end, a bar rigid with said frame between its ends and having an integral foot part offset laterally therefrom and extending toward the other end of the frame, the inner side of said foot part having a cutting edge on its upper side, another bar vertically reciprocable in said frame so as to pass closely by said inner side of said foot part and having a cutting edge on its lower end to cooperate with the cutting edge on said foot part, a lever overlying said handle means and pivoted to the other end of said frame beyond said other bar, and a roller on said lever engaging the upper end of said other bar so relative movement of the lever and frame will actuate said other bar in cutting movements, said roller having a flat thereon adapted to engage the frame and halt the lever in at least one of its extreme positions of movement, said roller being arranged relative to the pivot axis of said lever so the mechanical advantage of said lever increases as it moves to actuate said other bar in cutting movements.

7. In a shears comprising a frame extending generally longitudinally and having handle means at one end, a bar rigid with said frame between its ends and having a dependent integral foot part offset laterally therefrom and extending toward the other end of the frame, 75

the inner side of said foot part having a cutting edge on its upper side, a second bar vertically reciprocable in said frame so as to pass closely by said inner side of said foot part and having a cutting edge on its lower end to cooperate with the cutting edge on said foot part, a third bar rigid with the frame and upstanding therefrom forming with said first bar a rectangular passage in which the second bar reciprocates, a lever overlying said handle means and pivoted to said third bar, and a roller on said lever over said second bar, whereby movement of said lever about its pivot will actuate said other bar in cutting movements.

15. 8. In a shears comprising a frame extending generally longitudinally and having handle means at one end, a bar rigid with said frame between its ends and having a dependent integral foot part offset laterally therefrom and extending toward the other end of the frame, the inner side of said foot part having a cutting edge on its upper side, a second bar vertically reciprocable in said frame so as to pass closely by said inner side of said foot part and having a cutting edge on its lower end to cooperate with the cutting edge on said foot part, a third bar rigid with the frame and upstanding therefrom forming with said first bar a rectangular passage in which the second bar reciprocates, a lever overlying said handle means and pivoted to the said third bar, and a roller on said lever over said second bar, whereby movement of said lever about its pivot will actuate said other bar in cutting movements, said roller having a flat thereon 35 that engages said third bar and stops said lever at the end of a working movement thereof.

9. In a shears having a frame including a handle at one end; a first blade fixed in said frame adjacent the other end and dependent therefrom, 40 a second blade reciprocable in said frame in a direction generally perpendicular to the length of the frame, said blades having adjacent cutting edges generally perpendicular to the direction of reciprocation of said second blade, a lever pivoted on said frame between said second blade and the said other end of the frame, a roller on said lever bearing on the end of said second blade opposite the cutting edge thereon and forwardly of the center line thereof, and resilient means acting on said second blade for urging it away from said first blade to permit material to be cut to be inserted therebetween, said roller being so positioned that when said blades are open a line joining the pivot axes of the roller and lever is substantially parallel with said cutting edges whereby, as cutting of material by said blades proceeds, the mechanical purchase of said lever on said second blade increases.
